WINDING MECHANISM FOR TALKING MACHINES.
APPLICATION FILED JUNE 17, 1914.

1,312,624.

Patented Aug. 12, 1919.

UNITED STATES PATENT OFFICE.

LOUIS A. FREEDMAN, OF NEW YORK, N. Y.

WINDING MECHANISM FOR TALKING-MACHINES.

1,312,624.

Specification of Letters Patent. Patented Aug. 12, 1919.

Application filed June 17, 1914. Serial No. 845,551.

To all whom it may concern:

Be it known that I, LOUIS A. FREEDMAN, a citizen of the United States, and a resident of the city, county, and State of New York, (whose post-office address is 135 West 86th street, New York city,) have invented new and useful Improvements in Winding Mechanism for Talking-Machines, of which the following is a specification.

10 The object of my invention is to provide a device of this class which may be applied to any suitable talking machine provided with a cover, so that when the cover is raised or lowered, as the case may be, either or 15 both, the mechanism for driving the record is wound without the usual trouble incident to turning a crank after the machine is otherwise ready for operation. This object is 20 accomplished by my invention, several embodiments of which are hereinafter set forth, although it is to be understood that my invention is not restricted to the precise structures herein disclosed, but may be applied in many other ways, all of which come within 25 the scope of the claims.

For a more particular description of my invention, reference is to be had to the accompanying drawings, forming a part hereof, in which—

30 Figure 1 is a front elevation of a talking machine provided with my invention, a part of the casing being broken away to reveal the interior structure;

Fig. 2 is a transverse section of a portion 35 of the mechanism shown in Fig. 1, on the line 2—2 of Fig. 3, looking in the direction of the arrows;

Fig. 3 is a sectional view, taken on the line 3—3 of Fig. 2, looking in the direction 40 of the arrows;

Fig. 4 is a sectional view, taken on the line 4—4 of Fig. 3, looking in the direction of the arrows;

Figs. 5 and 6 are sectional views, taken 45 on the lines 5—5 and 6—6 of Fig. 4, looking in the direction of the arrows;

Fig. 7 is a sectional view, taken on the line 7—7 of Fig. 3, looking in the direction of the arrows.

50 Throughout the various views of the

drawings, similar reference characters designate similar parts.

In the preferred embodiment of my invention, as disclosed in the accompanying drawings, 1 indicates the instrument which is provided with a cover 2 and case 3, which may be of any suitable construction. The cover 2 is hinged to the case 3 by suitable hinges 4 and the cover may be held in an elevated position by means of the ordinary brace 5. The instrument is provided with the usual sound box arm 6, which is placed over the turntable 7. The turntable 7 is carried above the platform 8 and is driven by the vertical spindle 9 which carries the spiral gear or worm 10 which is driven by a suitable motor 11^a in the conventional manner.

The motor 11^a is provided with a main shaft or arbor 12^a on which is mounted a 70 ratchet wheel 28^a and pinion 14^a. These parts do not rotate backward during the unwinding of the motor 11^a, but remain at rest. A spring pressed pawl 29^a acting under the influence of a spring 30^a is mounted 75 on a bracket 13^a and not on the main driving gear 31^a. This pawl engages with the ratchet wheel 28^a preventing backward movement of the main shaft 12^a. The gear 14^a meshes with a corresponding pinion 14^b 80 on a shaft or arbor 54 suitably journaled in the bracket 13^a.

The crank usually found on talking machines for winding has been replaced on this shaft 54 by a friction clutch 52 and a 85 sprocket wheel 33 which is driven by a sprocket chain 34 which also passes over the main driving sprocket wheel 35 which will be described below. In this embodiment of my invention, either the raising or the lowering of the cover 2 will cause this sprocket wheel 35 to be driven in the same direction. The friction clutch is provided, as will appear below, to prevent an over-winding of the spring motor.

The cover 2 is provided with a suitable screw shaft 36 which is pivoted to said cover at 37 and passes down through the opening 20 in the platform 8, and also through a casting 38 fixed by suitable screws 39, or other- 95 100

wise, below said opening. This casing 38 has a suitable cover 40 held in place by suitable screws 40^a, and both the cover 40 and the casing 38 are slotted so as to permit the 5 screw shaft 36 to oscillate in this casing in a manner which will now be described.

In the casing 38, and below the cover 40 is mounted on the screw 36 a suitable nut 41 which has double threads engaging the 10 corresponding threads of the screw 36, the threads in each case having a large pitch, as shown. This nut 41 carries at each end a collar 42 which is fixed thereon, and against these collars are opposed double 15 bevel gears 43 and 44 which turn idly on this nut 41, and between these double gears are placed two ratchet wheels 45 and 46 which are fixed on the nut 41 and provided with suitable annular races for ball 20 bearings, and corresponding races are placed in the pivoted bearing 47 which is placed about the nut 41 at its center and between the ratchet wheels 45 and 46, as shown. Suitable spring pressed pawls 48 pivotally 25 mounted on the gears 43 and 44 permit these gears to revolve idly in one direction only, and force the same to turn in the other direction with the nut 41, and the nut 41 turns in one direction when the screw 36 goes 30 down, and in the other direction when the screw 36 goes up through the nut. A third beveled pinion gear 49 sleeves on the pivot of the center bearing 47 which is near the sprocket wheel 35, and the sprocket wheel 35 is placed on the same sleeve as the gear 49, and fixed thereto so that the pinion and sprocket revolve together. The result of 35 this construction, as above described, is that while the cover 2 is raised or lowered the sprocket wheel 35 is always driven positively in the same direction, and it is always driven so as to wind the motor 11^a of the talking machine. It will also be noted 40 that the center bearing 47 is pivotally connected to the casing 38 at each end so as to permit the necessary oscillation of the nut 41 while the screw 36 is moving in the direction of its axis through this nut which is also rotated about the pivot point 47 by 45 the pivot connection with the cover 37 causing the upper end of the screw to move in the arc of a circle whose center is the hinge 4. To prevent overwinding, the sprocket wheel 33 is provided with a suitable thrust ball 50 on its shaft 51 and this shaft 51 also carries one member of a suitable friction clutch 52, through which it is connected to arbor shaft 54 of motor 11^a. The clutch 52 is preferably secured instead of 60 the crank and the sprocket wheel 33 runs idle on the shaft 51 and is made to drive the shaft 54 by the ball bearing 50 with its cup 53 which engages a spring 55 which is pressed against the cup 53 by means of a 65 nut 56 which has lugs 57 that ride in the

parallel grooves 58 of a guide 59, which is suitably mounted at one end in a bracket 3^a secured to the under surface of platform 8 and at its other end against the casing 3. The shaft 51 is screw threaded to receive 70 the nut 56. This shaft 51 is also provided with a knurled thumb piece 59^a which is fixed thereon and adapted to turn it, and with a collar 60 with a roughened surface that is adapted to engage a corresponding 75 collar 61 fixed to the casing 3, so that under no circumstances will the shaft 51 revolve except when it is turned through the knurled end 59^a. From this it is obvious that by turning this end 59^a in one direction the tension of the spring 55 is increased, whereby the main spring of the motor 11^a may be wound tighter, and by turning the end 59^a in the other direction, the spring 55 is put under less tension, and thereby 85 the spring of the said motor 11^a is wound with less tightness before the slipping takes place in the friction clutch 52.

While I have shown and described one embodiment of my invention, it is obvious 90 that my invention is not to be restricted thereto but is broad enough to cover all structures coming within the scope of the annexed claims.

Having described my invention, what I 95 claim is:—

1. In a device of the class described, a casing, a movable cover, a spring motor, a screw shaft on said cover, and mechanism connecting said screw shaft and spring motor to cause the motor to be wound in one direction by raising or lowering said cover. 100

2. In a device of the class described, a casing, a cover, a spring motor, a screw shaft connecting the cover and spring motor, 105 mechanism engaging said screw shaft to cause a winding of the motor in one direction by either raising or lowering of the cover, a friction clutch on the winding mechanism and means for increasing and 110 decreasing tension on said clutch.

3. In a device of the class described, a casing, a cover connected thereto, a screw shaft pivotally secured to said cover, means engaging said screw shaft for rotating the 115 motor shaft in one direction by a raising or lowering of the cover, a friction clutch on the motor shaft, and means on the exterior of the casing for regulating tension on said clutch whereby slippage may be 120 caused at a desired point.

4. In a device of the class described, a casing, a cover connected to said casing, a screw shaft pivotally connected to said cover, a spring motor, and mechanism connecting said spring motor and the screw shaft so that said motor may be wound in one direction by raising or lowering said 125 cover.

5. In a device of the class described, a 130

casing, a cover, a hinge connecting said casing and cover, a screw shaft, a spring motor, a friction clutch connected to said motor, and mechanism connecting said friction clutch and screw shaft whereby said clutch may be driven to wind the motor whenever the cover is raised or lowered.

Signed at the city of New York, county of New York and State of New York, this 4th day of June, 1914.

LOUIS A. FREEDMAN.
